(57) CLAIM

The ornamental design for a portion of a handset, as shown and described.

DESCRIPTION

FIG. 1 is a perspective rear view of a portion of a handset showing my new design; and,
 FIG. 2 is a rear view thereof.

The broken line showing of the remainder of the handset is for illustrative purposes only and forms no part of the claimed design.

1 Claim, 2 Drawing Sheets
